ROLL FOR JORDAN TYPE PAPER PULP
REFINERS

Adam E. Bridge, Franklin, Ohio, assignor to The
Black-Clawson Company, Hamilton, Ohio, a
corporation of Ohio

Application June 22, 1936, Serial No. 86,446

6 Claims. (Cl. 92—27)

This invention relates to paper making machines and more particularly to rotatable rolls such as Jordan engine plugs and the like.

One object of the invention is the provision of a knife holding member, such as a Jordan engine plug in which a body member is provided with longitudinally extending slots which interfit with and receive the inwardly converging sides of knives or bars, the latter being adapted to be readily moved within the slots until their final seating engagement takes place.

Another object of the invention is the provision of a roll in which the bars are tightly fitted in the slots at the outer periphery of the roll.

Another object of the invention is the provision of a roll of the character mentioned having slots the sides of which converge inwardly, bands encircling the body being adapted for wedging engagement with the knives, which are in turn so shaped as to provide a wedging engagement with the roll body.

Another object of the invention is the provision of a Jordan engine plug or the like having a series of longitudinally extending knives or bars removably seated in a supporting body in outwardly extending slots which are rounded to provide unusual strength at the base of the lugs between slots, the knives interfitting with the body as to provide an assemblage which is maintained in a secure manner throughout very long periods of use.

Other objects and advantages of the invention will be apparent from the following description, the appended claims and the accompanying drawings, in which—

Fig. 1 is a side elevation of a Jordan engine plug embodying the present invention;

Fig. 2 is a side elevation of a portion of one of the knives or bars of the plug;

Fig. 3 is a longitudinal sectional view through the outer portion of the plug taken at one side of one of the knives as indicated by the line 3—3 of Fig. 4;

Fig. 4 is a section on the line 4—4 of Fig. 3;

Fig. 5 is an enlarged sectional view corresponding to Fig. 4; and

Figs. 6, 7, and 8 show a modified form of construction, Figs. 6 and 8 being transverse sectional views through the portion of the Jordan engine plug shown in Fig. 7 and taken on the lines 6—6 and 8—8 respectively.

Referring more particularly to the drawings by reference numerals, 10 designates generally the plug of a paper pulp refining unit such as a Jordan engine or the like. In such units the plug

body, which is frequently of a frusto-conical form, carries a series of knives which cooperate with another series of fixed knives that are provided on the interior of an outer housing body within which the plug is rotatably supported, 5 the outer body being of the same frusto-conical shape as the plug, and the knives on the plug and outer body operating with a suitable clearance so as to be just out of running contact with one another. The knives and knife separators 10 which are provided between adjacent knives are usually constructed as separate pieces assembled to the conical body.

In accordance with the present invention there is provision for very securely anchoring inwardly 15 tapering portions of the knives in longitudinally extending slots provided in the frusto-conical plug body, the latter being provided, in accordance with a preferred embodiment of the invention, with a plurality of annularly extending 20 knife retaining means or bands which are adapted for cooperation with suitable tongues and recesses on the inner portions of the knives. The latter are secured in position by a movement toward the plug axis and then by a longitudinal or 25 endwise movement along the slots, to a limited extent, as will be more fully described.

The Jordan plug 10 comprises a frusto-conical shell or body 11, preferably of cast iron or other suitable material, having a series of longitudinally 30 extending slots 12 in which the knives or bars 14 are held. As the circumference of the plug is considerably greater at its larger end, additional shorter slots are preferably provided at the larger end of the plug, as shown in Fig. 1, to accommodate a number of additional shorter knives which at this end of the plug alternate with the long knives 14. The slots extend inwardly from the outer frusto-conical surface 13 of the body 11, and although they could extend out rearwardly 40 at a suitable angle to the radial, it is preferred that they extend radially, as shown. The inner terminal parts of the slots are formed so as to be devoid of any sharp angles at the inner side corners or, in other words, at the inner ends of 45 the flat bar contacting sides where the slots are preferably rounded or curved as shown at 15. This gives an increased strength for the base of the lugs 16' which project from the main body portion of the roll between adjacent knives. This 50 increase of strength is due to the elimination of the sharp corners which are customarily present as in a flat bottom slot, these sharp corners having a weakening effect at the very point where the increased strength is desired. The increase 55

- of the strength at the base of the lugs is also due to the increased distance across the base of the lugs by reason of the fact that the inner portions of the slots curve towards the center of the slot.
- 5 As will be apparent, the width of the slot near the bottom of the slot is no greater than the width of the radially outer portions of the slot so that the width of the lug at its outside is large enough to permit the knives to be assembled by
- 10 a movement which is generally toward the roll axis. Furthermore, in accordance with the preferred form of the invention, the sides of each of the slots 12 preferably converge inwardly at an angle of a few degrees towards one another
- 15 as shown in Fig. 5 of the drawings so that a still greater lug width at the base of the lug is provided for. The inwardly converging cross-sectional shape of the slots combined with the curved formation of the inner terminal portions of the
- 20 slots give a very strong construction at the base of the lugs 16'. The curved formation of the inner terminal portions of the slots provide that the base portion of the lugs, at different distances inwardly toward the axis of the body member shall increase in width at a rapid rate
- 25 from the point where the curve starts to a maximum width which is at the same distance from the axis of the body member as the innermost portions of the slots, thus giving the maximum
- 30 lug width adjacent the very innermost portions of the slots.

The outer surface of the body 11 is cut away so as to provide a plurality of annular surface indentations 16 in the same manner as in the

35 prior application of H. D. Martindale, Serial No. 27,727 filed June 21, 1935, these surface indentations extending outwardly and preferably cylindrically toward the smaller end of the plug, the inner end of each surface indentation providing

40 a shoulder 17. Seated on or in each of the surface indentations is an annular knife retaining band 18, each abutting against a shoulder 17, and of such size as to lie entirely below the cone defined by the outer surface 13 of the plug body. The

45 several bands are, of course, of graduated diameters, and their inner surfaces are preferably substantially cylindrical so that they can be readily applied merely by moving them endwise towards the larger end of the plug, sliding along the cylindrical indentations 16 until they come up against their respective shoulders 17. These bands are

50 preferably shrunk in place.

The inner surface of each of the bands 18 is spaced some distance outwardly from the inner ends of the slots 12, and each knife, as shown in Fig. 2, is provided with recesses 21, suitably spaced apart along the inner portion of the knife in accordance with the longitudinal spacing of the bands 18. Tongues 22 are provided on the knives

55 by extending portions underlying parts of the recesses, these tongues having wedging surfaces 23 that extend at a slight angle to the inner edge of the knife so as to provide a wedging engagement with the inner sides of the bands 18 as the

60 knives are moved toward the larger end of the plug after being inserted in the slots. It will thus be understood that when the knife is moved endwise towards the larger end of the plug the wedging action that takes place between the tongues

65 22 of the knife and the bands 18 forces the knife inwardly towards the axis of the plug. And since the sides of the slots converge inwardly at a slight angle, with the sides of the knives also arranged at a corresponding angle, it will be clear that the

70 75 final seating action of a knife in a slot takes

place in a wedging manner, the parts being tightened up firmly in their final seating movements. However, before this final seating movement of a knife in a slot it will be apparent that the knife can move freely in a longitudinal direction without binding in any way on the sides of the slot. As indicated in Fig. 5, there is sufficient clearance provided between the inner ends of the knives and the inner ends 15 of the slots so that these portions are out of contact in order to provide a firm 10 engagement of the sides of the knife with the sides of the slot at their outer portions so as to prevent any looseness or movement when the knives are assembled.

The normal operating force on the knives, during operation, tends to move them toward the larger end of the shell and thus tends to tighten them in the slots. Additional means is preferably provided to hold the knives in their final assembled positions, such as a ring 25 assembled by shrinking it on the smaller end of the shell at the ends of the knives.

The knives 14 are seated in the slots throughout a very considerable portion of their radial depth, the slots 12 having a depth several times 25 their width. The knife thickness or slot width may be from three-sixteenths of an inch to one-half inch or of that order. As shown, somewhat in excess of one-third of the knives are seated in the slots below the conical surface 13 of the plug 30 body. Moreover nearly the entire length of the knife is in effective abutting contact with the sides of the slots so that a very large total area of contact is provided between the knife and the body, giving a very firm holding action on the 35 knives. The knives are preferably rigidified still further by means of filler pieces or woods 26 which are provided with grooves 27 adapted to receive longitudinal surface irregularities or projections 28 on the knives, so that the woods, which 40 are driven in endwise from the larger end of the plug, are securely held against any radial outward movement during operation. Since the knives are held against any looseness or movement the woods will be maintained tight. The radial depth 45 of the woods is preferably about the same as the slot depth but as the sides of a knife are parallel, see Fig. 5, where it projects from a slot (except for the surface irregularities 28) the sides of the woods are flat and the wood thickness can readily be made of any suitable extent to give the desired 50 space between knives outwardly of the woods. A suitable end plate 29 on the larger end of the plug may be employed to hold the woods against longitudinal movement. As shown in Fig. 5, the 55 tapering portion of each knife terminates substantially at the peripheral surface of the roll body, thus giving adequate bar strength where the knife engages the peripheral surface of the body and at points outwardly thereof.

A plug body made in accordance with this invention is exceedingly strong and very firmly anchors the inner ends of the knives in place against any looseness or movement, and moreover the construction of the plug body itself is 60 very greatly strengthened because of the slot form and the manner in which the knives are arranged in the slots. This increase in strength 65 of the roll body has been found to be 40% or more in excess of the strength of usual constructions 70 in which the present improvements are not utilized, the strength improvement being especially noticeable at the base of the lugs between which the knives are held, as it is at those points that 75 breakages would otherwise be apt to occur. This

breakage of the plug at the base of the lugs has been a fault of the usual plug construction having the usual flat bottom slot, as the right angle corner of the slot is then at the point of minimum lug width at the base of the lug.

With the inner portions of the sides of the knives inclined as above mentioned, the knives may be made of rolled steel in spite of the fact that the thickness of such commercial stock may 10 vary several thousandths of an inch, and the plug body may be made of cast iron, and the construction will have adequate strength as well as providing unusual ease in assembly and disassembly of the parts. As the seating movement of a knife in a slot takes place only during its final movement through a small part of an inch there will be no substantial broaching action of the sides of the knives or slots where they engage with one another. Wear produced by a 15 broaching action would make the slots roomier each time the knives are assembled and disassembled, and this is prevented in accordance with the construction of this invention, so that the knives will always be fitted tightly in the slot 20 at the outer periphery of the plug. If there is any wear of the slots or knives the latter will merely seat themselves a little deeper and maintain a tight fit. As will be apparent this is impossible in the usual slots having parallel sides. 25 And as will be quite apparent the removal of a bar can be readily accomplished, as a very small movement of the bar in a longitudinal direction loosens the bar from the slot, in spite of any rusting action that may have taken place, so that 30 the bar can then be very readily moved still further in a longitudinal direction and then entirely withdrawn from the slot by an outward movement, thus saving time and avoiding the danger of breaking the lugs that exists where 35 the slots and knives are of the customary form and where the knives must be driven out after 40 rusting.

Various modifications may be made in accordance with this invention. For example as 45 shown in Figs. 6, 7 and 8, the roll construction illustrated in those figures is one that employs knife receiving slots that are inwardly tapered and that have inner terminal portions so formed as to avoid the usual right angle corners, although in this form of construction the woods 50 or spacers are held in a somewhat different manner. As shown in these figures, the roll body 35 is provided with a series of spaced outwardly projecting portions 36, and these projecting portions 36 are longitudinally slotted as by means of the slots 37 the sides of which converge inwardly. The inner ends of the slots could be pointed or wedge-shaped at the center 55 but sharp angles at the inner terminal portion of the flat sides are avoided, preferably by curving or rounding those portions, as shown, so they will be entirely devoid of sharp angles or recesses. Each knife 38 is therefore supported at a series of spaced points along its length, the inner ends 40 of the knives having a clearance 60 spacing from the outer conical surface 41 of the roll and from the bottoms of the slots so that the inwardly tapering portions of the knives are firmly seated along their tapering sides in the tapered slots. In this construction the knives are provided with recesses 42 and wedging tongues 43 cooperating with the bands 44 which encircle the plug body. The bands 44 are suitably secured to cylindrical surfaces provided on

the outwardly projecting portions 36 of the plug body.

In this form of construction the filler pieces 46, of suitable material but preferably of wood, are notched as indicated at 47 in Fig. 7 so as to receive the outwardly extending projecting portions 36 of the roll body. The inner portions of the wood spacers, which are assembled when dry, expand outwardly below the line 48 defining the inner extent of the parallel side portion or 10 the knife, so as to fit against the tapered sides of the knives, and expand into slots 45 in the knives, and are also retained in place by additional suitable means such as a readily fusible metal skeleton 50 applied by pouring a suitable 15 melted metal into small passages in the spacers 46, the latter and the knives having communicating channels into which the metal flows so that when the metal solidifies the knives and the woods are adequately secured together. As will 20 be understood, the woods or filler pieces 46 instead of being driven in endwise from the larger end of the plug body as in the form of construction first illustrated, are applied by merely moving them radially inwardly, followed by the securing action provided as by pouring the melted metal as above mentioned.

While the forms of apparatus herein described constitute preferred embodiments of the invention, it is to be understood that the invention 30 is not limited to these precise forms of apparatus, and that changes may be made therein without departing from the scope of the invention which is defined in the appended claims.

What is claimed is:

1. A roll of the character described for paper machines comprising a rotatable body having an outer frusto-conical surface provided with an annular series of radial slots in which the outer parts of the slot sides are flat and relatively inclined so as to converge inwardly with the inner ends of the slots terminating in rounded surfaces so as to be devoid of sharp angles, a series of knives having their inner portions converging inwardly and fitting in said slots with the radially inner ends of the knives having at least a clearance distance from the inner ends of the slots, said body having a plurality of annular surface indentations, a series of bands on said series of surface indentations with the inner surface of the bands spaced outwardly of the inside of the slots and with the outer sides of said bands located inwardly of the cone defined by the outer surface of said body, said knives having portions adapted for interlocking engagement with said bands to provide a wedging engagement of said knives and said slots in a radially inward direction, and spacers on the outer surface of said body and extending between adjacent knives.

2. A roll of the character described for paper machines comprising a rotatable body provided with an annular series of slots elongated in the direction of the length of the body member, the sides of each slot converging inwardly from their outer ends, a series of knives adapted for assembly by movement inwardly into the body followed by relatively short longitudinal movement, said knives having their inner portions converging inwardly at opposite sides thereof and fitting in said slots and being provided with recesses in their inner portions extending from their inner edges and providing holding surfaces which are slightly inclined to the inner edges of the knives, the inner ends of the knives throughout their length having at least a clearance distance from

the bottoms of the slots for tight engagement of the sides of the knives with the inwardly converging sides of the slots, and means adapted for interlocking wedging engagement with said holding surfaces of the knives for holding said knives in said body.

5. A roll of the character described for paper machines comprising a rotatable body provided with an annular series of outwardly extending slots, the sides of each slot converging inwardly, a series of knives having side portions projecting from said slots and having inner portions converging inwardly and fitting in said slots, said knives having a length substantially equal to the 10 length of the slot in which it fits and being adapted for assembly by movement inwardly into the body followed by relatively short longitudinal movement, the inner ends of the knives having at least a clearance distance from the bottoms 15 of the slots, and means fitting into said knives for drawing said knives inwardly toward the central axis of said body as the knives are moved longitudinally.

4. A roll of the character described for paper 25 machines comprising a frusto-conical rotatable body provided with an annular series of outwardly extending slots which extend continuously the length of the body, the sides of each slot converging inwardly, a series of knives 30 adapted for assembly by movement inwardly of the body followed by relatively short longitudinal movement and having their inner portions converging inwardly and seated in said slots, the seated portions of said knives being about one-third the radial width of the knife, and means 35 extending annularly on said body between the ends of the knives for pulling said knives inwardly in the body member into wedging engagement with the converging sides of the slots 40 as the knives are moved longitudinally.

5. A roll of the character described comprising a rotatable knife holding body extending continuously at the outer portion thereof from one end of the roll to the other and provided with a 45 series of outwardly extending slots elongated in

the direction of the length of the body member, the sides of each slot converging inwardly and the inner end of each slot being devoid of sharp corners at the sides thereof and having no greater width than any radially outer portion of the slot, 5 a series of knives seated deeply in said slots and adapted for assembly by movement inwardly into the body followed by relatively short longitudinal movement, said knives having side portions projecting outwardly from the surface of the body 10 with the bottoms of the knives throughout their length spaced from the bottoms of the slots, and means on said body member and in wedging engagement with said knives between the ends of the knives to force the same inwardly as the 15 knives are moved longitudinally.

6. A roll of the character described comprising a rotatable body having an outer frusto-conical surface provided with an annular series of outwardly extending slots which extend throughout 20 the length of the body, the outer parts of each slot being flat and relatively inclined so as to converge inwardly with the inner ends of the slots terminating in rounded surfaces so as to be devoid of sharp angles, a series of knives adapted 25 for assembly by movement inwardly into the body followed by relatively short longitudinal movement, said knives having their inner portions converging inwardly and fitting in said slots with at least a clearance distance between the 30 bottom of a knife and the bottom of a slot and with the thickness of the knife decreasing progressively inwardly from the portion of the knife adjacent the outer end of the slot, said body having a plurality of annular surface indentations, 35 a series of bands on said series of surface indentations with the inner surface of the bands spaced outwardly of the inner sides of the slots and with the outer sides of said bands located inwardly of the cone defined by the outer surface of said body, said knives having portions adapted for interlocking wedging engagement with said bands to move the knives inwardly as they move longitudinally.

ADAM E. BRIDGE. 45
